CLAIM

An ornamental design for a fishing jig, as shown and described.

DESCRIPTION

FIG. 1 is a perspective view of a fishing jig.

FIG. 2 is a right side view of the fishing jig of FIG. 1.

FIG. 3 is a left side view of the fishing jig of FIG. 1.

FIG. 4 is top view of the fishing jig of FIG. 1.

FIG. 5 is a bottom view of the fishing jig of FIG. 1.

FIG. 6 is a front view of the fishing jig of FIG. 1; and,

FIG. 7 is a rear view of the fishing jig of FIG. 1.

The broken lines depict environmental structure and are for illustrative purposes only and form no part of the claimed design.
